UNITED STATES PATENT OFFICE

168,014

ORNAMENTAL CHAIN

Gottlob Armbrust, Providence, R. I.

Application August 4, 1949, Serial No. 4,303

Term of patent 3½ years

(Cl. D45—16)

To all whom it may concern:

Be it known that I, Gottlob Armbrust, a citizen of the United States, residing at Providence, in the county of Providence and State of Rhode Island, have invented a new, original, and ornamental Design for an Ornamental Chain, of which the following is a specification, reference being had to the accompanying drawing, constituting a part hereof.

Fig. 1 is a top plan view of an ornamental chain, showing my new design; and

Fig. 2 is a side view thereof.

I claim:

The ornamental design for an ornamental chain, substantially as shown.

GOTTLOB ARMBRUST.
